UNITED STATES PATENT OFFICE.

FRANZ JANECEK, OF KARLIN, NEAR PRAGUE, AUSTRIA-HUNGARY.

ELECTRIC-ARC LAMP.

No. 844,361.

Specification of Letters Patent.

Patented Feb. 19, 1907.

Application filed November 22, 1905. Serial No. 288,590.

To all whom it may concern:

Be it known that I, FRANZ JANECEK, subject of the King of Bohemia, residing at Karlin, near Prague, Bohemia, Austrian Empire, have invented certain new and useful Improvements in Electric-Arc Lamps; of which the following is a specification.

The present invention has reference to improvements in electric-arc lamps, and relates 10 more especially to improvements in means for regulating the feed of the carbons and the formation of the light arc; and the invention specifically consists of the construction, arrangement, and coöperation of parts, as hereinafter described, and set forth in the appended claims, reference being had to the accompanying drawings, in which—

Figure 1 represents a view in elevation, partly in section, of an arc-lamp embodying 20 my improvements; Fig. 2, a view in elevation, partly in section on a plane at right angles to that of the sectional portion of Fig. 1; and Figs. 3 and 4 are detail views.

The two carbon rods A and B are held in 25 the clamps a' b', and the latter are slidably arranged on the guide-rods a a and b b. The rods a for the positive carbon A are secured above in the top plate 1 and below in the disk 2, rigidly held in the bottom casing 3, 30 with the result that this carbon rod A can only move in the direction of its longitudinal axis, while the negative carbon B, as will be described later on, can also move sidewise through definite range. The carbon A is 35 provided with a series of little pins c, of metal or other suitable material, the lowermost of which always rests upon the contracted rim 5 of the ring d, which latter in turn rests upon the flange 4 of the casing 3, as clearly shown 40 in Fig. 2. The ring d can readily be rotated on its seat, while, as before stated, the disk 2 is rigidly secured in the casing in suitable manner. It is obvious that this rotatable ring d must be of non-conducting apyrous 45 material, and being above the arc does not interfere with the projection of the light-rays. The pins c are of such material that the pin resting upon the rim 5 under the influence of the heat and weight of the carbon by degrees "gives," bending upwardly, melts, or burns up, and thereby allows the carbon A, and with it the carbon B, to slowly descend in measure. Upon one pin leaving the rim 5 the succeeding one drops unto the rim, and 55 the described operation repeats itself.

Upon one point of the rim 5 becoming

damaged by the pins the ring d is rotated a little distance and a new point of support offered.

The guide-rods b for guiding the clamp b' 60 for the negative carbon B are secured above to an axle 6, which is provided with lever-weights 8 and journaled in cheeks 7, depending from the top plate. To this axle is secured, by means of loop 9 and contact-screw 65 10, the one end of a metal band e, which is carried over the pulleys 11 and 12 and is secured with its other end to the top plate 1 by means of loop 9' and contact-screw 10'. The upper pulley 11 is journaled in a rigid bearing 11', while the lower one, 12, is rotatably mounted in a bracket 13, which is adjustable in height. This bracket 13 is clamped, by means of a screw 24, in a circumferential groove in a nut 20, which works on a thread 75 13^a on a sleeve 21, slidably mounted on a rod 22 and secured in any position on the rod by means of a set-screw 23. The collar 20 being adjusted to approximately the proper position and secured by the screw 23, further 80 adjustment of the height of the bracket 13 may be obtained by turning the nut 20 by means of a milled collar 13^b, and thus adjusting the nut and bracket on the adjusted collar. 85

The lamp not being used, the metal band is shortest and the two carbons touch at the lower ends. Upon current passing through the band it heats up and stretches, allowing the axle 6 to turn under the weights 8, with 90 the result of spreading the carbons. The current passes in the following direction: terminal 14, Fig. 1, positive carbon A, negative B, binding-screw 10, metal band e, binding-screw 10', magnets 15 15', and terminal 14'. 95

The suspension of the negative carbon is shown in Fig. 2. The clamp a' supports a sleeve 16, also sliding on one of the guide-rods a and having an arm 17. The clamp b' carries a similar arm 19, and both are connected by means of a chain or cord 18. It is obvious that the negative electrode is thereby enabled to follow by its own weight the descent of the positive carbon. 100

A lamp of the type described may be used 105 in a continuous as well as in an alternating current circuit, in which latter case no self-induction will obtain.

What I claim is—

1. The combination, in an electric-arc 110 lamp of a carbon, a series of pins projecting laterally from said carbon the lower one of

which is rendered inoperative by the heat of the arc, and means for supporting the lowermost pin while it remains operative, substantially as described.

5. The combination, in an electric-arc lamp of a carbon, a series of pins projecting laterally from said carbon, the lower one of which is rendered inoperative by the heat of the arc, and adjustable means for supporting the lowermost pin while it remains operative, whereby a new, unburned portion of the supporting means may be utilized when desired, substantially as described.

15. The combination, in an electric-arc lamp of a carbon, a series of pins projecting laterally from said carbon, the lower one of which is rendered inoperative by the heat of the arc, a ring receiving the lower end of the carbon, and an inner annular rim on said 20 ring supporting the lowermost pin while it remains operative, substantially as described.

4. The combination, in an electric-arc lamp of a carbon, a series of pins projecting laterally from said carbon, the lower one of

which is rendered inoperative by the heat of the arc, a ring receiving the lower end of the carbon, and an inner annular rim on said ring supporting the lowermost pin while it remains operative, said ring and rim being rotatably adjustable, whereby a new unburned portion thereof may be utilized when desired, substantially as described. 25 30

5. The combination, in an electric-arc lamp, of two carbons arranged side by side, a series of pins projecting laterally from one of said carbons, the lower pin being rendered inoperative by the heat of the arc, and means for supporting the lowermost pin while it remains operative, the other resting with its point lying against the supported carbon and feeding down with it, substantially as described. 35 40

In testimony whereof I affix my signature in presence of two witnesses.

FRANZ JANECEK.
